UNITED STATES PATENT OFFICE.

JACOB D. KISER, OF ELYRIA, OHIO.

FUEL-ATOMIZER.

1,094,075.

Specification of Letters Patent. Patented Apr. 21, 1914.

Application filed July 31, 1913. Serial No. 782,389.

To all whom it may concern:

Be it known that I, JACOB D. KISER, a citizen of the United States, residing at Elyria, in the county of Lorain and State 5 of Ohio, have invented a new and useful Fuel-Atomizer, of which the following is a specification.

This invention relates to atomizers for liquid fuel such as used in connection with 10 hydrocarbon engines, one of its objects being to provide a simple and efficient structure of this type which can be applied readily to an engine and which has means whereby the amount of fuel supplied to the 15 engine can be minutely regulated either prior to or during the operation of the engine so that complete combustion can be effected under all conditions.

Another object is to provide improved 20 means for mixing the air and oil.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, can be made within the scope of what is claimed, without 30 departing from the spirit of the invention.

In the accompanying drawings the preferred form of the invention has been shown.

In said drawings:—Figure 1 is an elevation of the atomizer, a portion of one of the 35 adjusting elements being shown in section. Fig. 2 is a section through the device on line A—B Fig. 1, the casing of the nozzle being shown in section so as to illustrate the controlling means therein in elevation. Fig. 3 is an enlarged central longitudinal section through the valve mechanism of the 40 nozzle, the central needle being shown in elevation. Fig. 4 is an enlarged section on line C—D Fig. 3. Fig. 5 is an enlarged section on line E—F Fig. 3. Fig. 6 is an enlarged section on line G—H Fig. 3. Fig. 7 is an enlarged section on line I—J Fig. 3. Fig. 8 is an enlarged section on line K—L Fig. 3.

50 It is to be understood that the atomizer herein described can be adapted for use in connection with different types of hydro-

carbon engines and, therefore, I do not desire to restrict myself to the particular mounting of the parts shown in the drawings. 55

In the drawings 1 designates a block adapted to be bolted or otherwise secured to the cylinder and from this block extends a nozzle casing 2 projecting through the head 60 of the cylinder, a portion of which is shown at 3. Nozzle casing 2 has a bore 4 which extends into the block 1, the outer end of the bore being counter bored as at 5 while the inner end is tapered, as at 6, to a small outlet orifice 7. Arranged in the bore 4 is a valve the construction of which is shown more particularly in Figs. 3 to 8 inclusive. This valve includes a central tubular core 8, 65 one end of which is externally screw threaded, as shown at 9 while its other end is provided with a frusto-conical head 10 having ports 11 at desired intervals, these ports diverging away from the adjacent end of the core 8. 70

A sleeve 12 is mounted for rotation on the core and abuts at one end against the annular shoulder 13 formed by the inner end of head 10, this abutting end of the sleeve being formed with an annular flange 14 in 80 which are provided peripheral notches 15 spaced apart distances equal to the distances between the ports 11. 75

That end of sleeve 12 remote from flange 14 is provided with diametrically opposed 85 notches 16 and fits within a counter bore 17 formed in a ring 18. The ring 18 fits loosely on the upper threaded end of the sleeve so as to be slipped therefrom readily but this ring is held against displacement relative 90 to the sleeve by a collar 19 which is screwed onto the threaded end 9 of the sleeve 8 and is preferably externally screw threaded, as shown at 20. A set screw 21 may be provided for fastening the collar to the sleeve 8. 95

A groove 22 is formed in the periphery of the ring 18 and has a pivot pin 23 extending thereacross, this pivot pin or screw projecting beyond the exposed face of ring 18 and into the path of a stop arm 24 which projects radially from the collar 19. Lugs 25 are located in the counter bore 17 and extend from ring 18, these lugs fitting within the notches 16 so that sleeve 12 and ring 18 100

are thus caused to rotate together as long as the ring is held in engagement with the sleeve by means of the collar 20.

Mounted upon the inner sleeve 12 is a small outer sleeve 26 having a conical end 27 which abuts against flange 14. This sleeve has an annular groove 28 and the periphery of the sleeve is provided at opposite sides of the groove with annular series of crossed grooves 29 communicating at their points of intersection and opening into the annular groove 28 and through the ends of the sleeve 26. Sleeve 26 is secured to the core 8 by means of a screw 30 or the like which extends through a slot 31 formed in the inner sleeve 12. This will be apparent by referring to Fig. 7. Thus it will be seen that when the core 8 is rotated the small outer sleeve 26 will move therewith, this movement relative to the inner sleeve 12 being limited by the screw 30 coming against one or the other of the ends of slot 31.

Another larger outer sleeve 32 is mounted for rotation on the inner sleeve 12 and abuts at one end against the small outer sleeve 26 while its other end is provided with an annular flange 33 provided in its periphery with a groove 34. A pivot screw 35 or the like extends across the groove 34 and upwardly into a segmental recess 36 formed in the periphery of ring 18. The pivot screw 35 co-operating with the wall of groove 36, serves to limit the relative rotation of sleeve 32 and sleeve 12.

Sleeve 32 is provided with a series of annular grooves 37 and formed in the outer surface of the sleeve between these grooves are annular series of crossed grooves 38 which communicate and open into the annular grooves 37. The end series of grooves 38 nearest sleeve 26 discharge through the end of sleeve 32 so as to partly or entirely register with the grooves 29 formed in sleeve 26 or to close the adjacent ends of said grooves 29.

The sleeves 26 and 32 fit snugly within the casing 2 so that any fluid, in order to pass from one end to the other of said casing, must travel within the intersecting grooves 38 and 29 and across the grooves 37 and 28 before entering the notches 14 and ports 11 and then passing to the outlet 7.

The port 7 is adapted to be closed by means of a needle valve 39 slidably mounted in the core 8 and adapted to be operated by the valve mechanism ordinarily provided upon hydrocarbon engines so that the port 7 will be opened at desired intervals.

For the purpose of effecting the desired adjustment of the parts of the atomizer herein described, adjusting means such as shown particularly in Figs. 1 and 2 are provided. A rod 44 extends into the groove 22 and is pivoted on pin 23, this rod 44 being adapted to slide within a gland 45 whereby

leakage is prevented. A slot 46 is provided in the rod and projecting into this slot is the rounded end 47 of a lever 48. This lever is fulcrumed on a bracket 49 and can be provided with a handle 50 whereby the same can be manipulated readily. Furthermore a stop screw 51 can be provided for limiting the swinging movement of the lever in one direction. It will be understood that by shifting lever 48 rod 44 can be moved inwardly or outwardly, thereby to cause the ring 18 to rotate. Sleeve 12 will also be rotated so as to move the notches 15 into or out of register with the ports 11, thereby regulating the amount of fuel discharged into the outlet end of the casing 2. During this rotation of the inner sleeve 12, the core 8 and the outer sleeve 26 will be held stationary by collar 19 which can be placed in engagement with any fixed structure. A rod 40 extends into the groove 34 and is pivoted on the pin 35, this rod being mounted to slide in a gland 41 located in the block 1. The outer end portion of the rod is screw threaded and is engaged by an adjusting nut 42 held against movement toward or from the block 1 by holding bracket 43. Obviously by rotating the nut, rod 40 can be shifted inwardly or outwardly relative to block 1 so as thus to rotate flange 33 and outer sleeve 32 and to move the said sleeve relative to sleeve 26 and bring the end series of grooves 38 into or out of register with the adjacent series of grooves 29.

It will be seen that when a mixture of air and oil is admitted to the space between sleeve 32 and casing 2 it can only pass to the outlet port 7 after traveling through the intersecting grooves 38 and 29. By shifting sleeve 32 relative to sleeve 26, in the manner hereinbefore described, communication between the grooves 38 and 29 can be partly or entirely cut off, thus regulating the amount of fuel supplied to the port 7.

Obviously as the air and hydrocarbon supplied to the space between sleeve 32 and casing 2 are caused to flow along the intersecting grooves 38 and 29, they will become thoroughly commingled and, when the needle valve 39 is shifted to open position, the explosive mixture will be sprayed through the ports 11 and 7, the said mixture being broken up into such small particles that ignition can be effected readily and completely. Importance is attached to the fact that the adjustment of the parts can be effected while the engine is in operation, this adjustment being so minute that any predetermined quantity of fuel found necessary to produce the best results can be directed into the cylinder. Not only can the amount of mixture supplied to the ports 11 be regulated by the relative movement of the parts 26 and 32, but the size of the jets discharged through the ports 11 can be regu-

lated by the relative adjustment of the parts 10 and 12.

It will be seen that the parts are so assembled that they can be removed readily for the purpose of cleaning and repairing them, the entire valve structure being liftable readily from the casing 2 simply by disconnecting the rods 40 and 44 from their pivot screws or pins.

10 What is claimed is:—

1. An atomizer including a casing having an outlet, a core stationary within the casing and having ports converging toward said outlet, a needle valve within the core for closing the outlet, and means revoluble upon the core for controlling the admission of fuel to the ports from the interior of the casing, said adjusting means including a slidable rod, means for shifting said rod, and means operated by the rod and having spaces normally registering with the ports.

2. An atomizer including a casing having an outlet, a core stationary within the casing and having ports for directing jets of fuel into the outlet, a needle slidable in the core for closing the outlet, a member mounted for rotation on the core and having notches adapted to register with the ports, and means for rotating the sleeve to shift the notches out of register with the ports.

3. An atomizer including a casing having an outlet, a core stationary within the casing and having ports for directing jets of fuel into the outlet, a needle slidable in the core for closing the outlet, a member mounted for rotation on the core and having notches adapted to register with the ports, and means for rotating the member to shift the notches out of register with the ports, said means including a tangentially disposed slidable rod, and means for shifting the rod.

4. An atomizer including a casing having an outlet, a core stationary within the casing and having ports for directing jets of fuel into the outlet, a needle slidable in the core for closing the outlet, a member mounted for rotation on the core and having notches adapted to register with the ports, means for rotating the member to shift the notches out of register with the ports, said means including a tangentially disposed slidable rod, means for shifting the rod, and means for holding the rod against movement.

5. An atomizer including a casing having an outlet, a tubular core fixedly mounted therein and having ports in one end for directing jets of fuel through the outlet, a needle valve slidable within the core and normally closing the outlet, a sleeve mounted for rotation on the core and having a notched flange, said notches normally registering with the ports, a stationary outer sleeve extending around the first named sleeve and fitting snugly within the casing, said outer sleeve having communicating

crossed grooves in its periphery for the passage of a combustible mixture between the outer sleeve and the casing, and means for rotating the inner sleeve independently of the core and outer sleeve.

6. An atomizer including a casing having an outlet, a tubular core fixedly mounted therein and having ports in one end for directing jets of fuel through the outlet, a needle valve slidable within the core and normally closing the outlet, a sleeve mounted for rotation on the core and having a notched flange, said notches normally registering with the ports, a stationary outer sleeve extending around the first named sleeve and fitting snugly within the casing, said outer sleeve having communicating crossed grooves in its periphery for the passage of a combustible mixture between the outer sleeve and the casing, means for fixedly securing the outer sleeve to the core, said inner sleeve having a slot for the reception of said means, and means for rotating said inner sleeve independently of the core and outer sleeve.

7. An atomizer including a casing, a tubular core fixedly mounted therein and having ports for directing jets of fuel through an outlet in the casing, a needle valve within the core for normally closing the outlet in the casing, an inner sleeve mounted for rotation upon the core and having notches in one end thereof normally registering with the ports, an outer sleeve connected to the core and having crossed communicating peripheral grooves, said outer sleeve fitting snugly against the casing and said grooves constituting passages for an explosive mixture passing to the ports from the interior of the casing, an outer sleeve mounted for rotation upon the inner sleeve and having series of crossed communicating peripheral grooves constituting passages for a combustible mixture, and independent means for rotating the outer revoluble sleeve and the inner sleeve separately.

8. An atomizer including a casing, a tubular core fixedly mounted therein and having ports for directing jets of fuel through an outlet in the casing, a needle valve within the core for normally closing the outlet in the casing, an inner sleeve mounted for rotation upon the core and having notches in one end thereof normally registering with the ports, an outer sleeve connected to the core and having crossed communicating peripheral grooves, said outer sleeve fitting snugly against the casing and said grooves constituting passages for an explosive mixture passing to the ports from the interior of the casing, an outer sleeve mounted for rotation upon the inner sleeve and having series of crossed communicating peripheral grooves constituting passages for a combustible mixture, and inde-

4

pendent means for rotating the outer revoluble sleeve and the inner sleeve separately, said fixed and revoluble outer sleeves having their crossed grooves movable into 5 and out of register.

9. An atomizer including a casing having an outlet, a core mounted therein, a needle valve for closing the outlet, said valve extending through the core, a stationary outer 10 sleeve fixedly connected to the core and having intersecting crossed and annular grooves constituting passages for an explosive mixture flowing toward the outlet, an outer sleeve mounted for rotation and having intersecting crossed and annular grooves constituting passages for an explosive mixture, certain of the grooves on the revoluble sleeve normally registering with certain of the 15 grooves on the stationary sleeve, and means 20 for rotating said revoluble sleeve to move the grooves into and out of register.

10. An atomizer including a casing having an outlet, a stationary sleeve fitted snugly in the casing and having intersecting crossed and annular grooves in its periphery and coöperating with the inner wall 25 of the casing to form communicating passages for an explosive mixture flowing to the outlet, a second sleeve mounted for rotation 30 in the casing and having communicating crossed and annular grooves coöperating with the inner wall of the casing to form communicating passages for an explosive mixture, certain of the grooves in

the last named sleeve being adapted to register with certain of the grooves in the first 35 named sleeve, and means for rotating the revoluble sleeve to shift said grooves into and out of register with the grooves in the other sleeve.

11. An atomizer including a casing having an outlet, a stationary sleeve fitted snugly in the casing and having intersecting crossed and annular grooves in its periphery and coöperating with the inner 40 walls of the casing to form communicating 45 passages for an explosive mixture flowing to the outlet, a second sleeve mounted for rotation in the casing and having communicating crossed and annular grooves coöperating with the inner wall of the casing to form communicating 50 passages for an explosive mixture, certain of the grooves in the last named sleeve being adapted to register with certain of the grooves in the first 55 named sleeve, means for rotating the revoluble sleeve to shift said grooves into and out of register with the grooves in the other sleeve, and means for limiting the rotation 60 of the revoluble sleeve.

In testimony that I claim the foregoing as my own, I have hereto affixed my signature in the presence of two witnesses.

JACOB D. KISER.
